The light therapy devices are characterized by an elongate box shape displaying a plurality of LED circular lenses

(Continued)

arranged in rows, each row being offset from a row above and/or below by approximately one half the diameter of an LED lens; ventilation openings in the left and right sides are arranged in a repeating slanted pattern as shown on reproductions 1.4, 1.5, 2.4, 2.5, 3.4, and 3.5; design variations include the relative proportions of the box dimensions and the number of LED lights (shown as an array of circles on reproductions 1.2, 2.2 and 3.2) in the related designs submitted. The broken lines shown in the drawings are for the purpose of illustrating portions of the light therapy devices that form no part of the claimed design.
